To all whom it may concern:

Be it known that I, Anna Konelsky, a citizen of the United States, residing at New York, in the county and State of New York, have invented a new, original, and ornamental Design for a Lady's Handbag, of which the following is a specification, reference being had to the accompanying drawings, forming part thereof.

Fig. 1 is a perspective view of a lady's handbag embodying my new design;

Fig. 2 is a perspective view showing the handbag in the opened position; and

Fig. 3 is a front view.

I claim:

The ornamental design for a lady's handbag, substantially as shown.

ANNA KONELSKY.
